UNITED STATES PATENT OFFICE

127,900

DESIGN FOR A SERVING BAR

Oscar I. Block, Chicago, Ill.

Application December 20, 1940, Serial No. 97,506

Term of patent 3½ years

To all whom it may concern:

Be it known that I, Oscar I. Block, a citizen of the United States, residing at Chicago, in the county of Cook and State of Illinois, have invented a new, original, and ornamental Design for a Serving Bar, of which the following is a specification, reference being had to the accompanying drawing, forming a part thereof.

In the drawing:

Fig. 1 is a top plan view of a serving bar embodying my new design;

Fig. 2 is a side elevational view of the same; and

Fig. 3 is an end elevational view of the same.

I claim:

The ornamental design for a serving bar, as shown.

OSCAR I. BLOCK.
